UNITED STATES PATENT OFFICE.

WILLIAM HOOPES AND THEODORE VARNEY, OF PITTSBURGH, PENNSYLVANIA.

TROLLEY-CONDUCTOR.

1,157,393.

Specification of Letters Patent.

Patented Oct. 19, 1915.

Application filed July 17, 1914. Serial No. 851,463.

To all whom it may concern:

Be it known that we, WILLIAM HOOPES and THEODORE VARNEY, citizens of the United States, and residents of Pittsburgh, in the 5 county of Allegheny and State of Pennsylvania, have invented a new and useful Improvement in Trolley-Conductors, of which the following is a specification.

Our invention relates to overhead electric 10 railway structures and particularly to structures of the so-called catenary type.

One object of our invention is to provide a composite trolley conductor the parts of which may be easily and cheaply manufactured and readily and expeditiously assembled and attached to a supporting structure.

Another object of our invention is to provide a conductor of relatively light weight that shall have a large current-carrying capacity and such strength and rigidity as to adapt it to withstand the heavy pressure and shocks of current-collecting devices that are employed upon such railway locomotives and cars as are operated at high speeds.

A further object of our invention is to provide a conductor of the character above indicated that automatically compensates for expansion and contraction, under changes in temperature, without danger of 25 buckling or being subjected to undue strains, at any season of the year or under any operating conditions.

In the operation of railways by electricity, the tendency is toward the use of high voltages and large amounts of power. Heretofore, when high voltages have been employed, conductor wires of comparatively small cross-section similar to those which have been used on so-called trolley roads, 35 have been suspended over the track by means of supporting structures of the catenary or other type.

On account of the high voltage and on account of the trouble due to ordinary trolley 45 wheels leaving the wire at high speeds, it has generally been necessary to use some form of sliding shoe or roller collector. Furthermore, on account of the necessity of having the wire sufficiently high above the 50 rail to clear ordinary freight cars having men on them, and also because there are usually low bridges or other obstructions which require the wire to be lowered at certain points, the framework which supports the

collecting shoe has necessarily been of such 55 substantial construction that very considerable pressure has been necessary to keep the collector in contact with the wire.

It has also been found that the various forms of small wire conductors suspended 60 over the tracks and kept taut under a relatively high longitudinal stress have caused difficulty, on account of changes in temperature. Devices, embodying springs, have been tried for maintaining a comparatively uniform 65 tension on the conductor wire but, on account of the high tension, such devices have been very heavy, cumbersome, and, in the main, unsatisfactory.

The most successful type of stationary 70 conductor which has been used, in so far as the collection of current therefrom by a moving train is concerned, has been the third rail. The reason for this has been that the rail is rigid and has a relatively large amount 75 of transverse stiffness so that relatively heavy pressure may be employed in the collecting shoe without producing distortion of the conductor. When, however, it is necessary to use high voltages, as well as to 80 meet certain other conditions of service, it is advisable to have the conductor overhead rather than beside the track.

Our present invention is designed to combine, in an overhead conductor, suitable for 85 use with high voltages, the mechanical running qualities of the third rail.

In the accompanying drawing, Figure 1 is a side elevational view of a portion of one of our trolley conductors, parts being broken 90 away. Fig. 2 is a plan view of the parts shown in Fig. 1. Fig. 3 is a sectional view taken on the line A—A of Fig. 1, and Fig. 4 is a diagrammatic plan view of a longer section of conductor than is shown in Figs. 95 1 and 2.

The portions of our trolley conductor that are preferably suspended from a catenary steel cable, in accordance with well known practice, are strips 1 and 2 of copper, aluminum or other metal of relatively high conductivity that may be of any desired length and cross sectional area. For convenience in handling and mounting and for satisfactory performance in service, the strips may advantageously be made approximately one fourth inch in thickness, two inches in width and three hundred feet in length, but mate-

rial variations from these dimensions are, of course, permissible. In order to provide for expansion and contraction, under changes in temperature, we make the strips 1 and 2 of wave form, as indicated in the drawing.

Contact pieces or shoes of any desired material, length and cross sectional shape are clamped to the lower edges of the conductor strips 1 and 2 by any suitable means to be engaged by trolley contact devices and thus relieve the strips from the wear to which they would otherwise be subjected. As shown in the drawing, the contact shoes 3 are of inverted T-shape and are clamped between some or all of those portions of the strips 1 and 2 that are in juxtaposition to each other, bolts 4 being preferably employed for this purpose. The pieces 3 are preferably formed of some tough hard metal, such as galvanized steel, and their bottom portions are convexly curved laterally, as indicated in Fig. 3. The ends of the pieces 3 are preferably scarfed to provide a smooth, uninterrupted contact surface for the current collector and are spaced apart a slight distance to permit of expansion and contraction under changes in temperature.

The end portions of the pieces 3 that are located between spread-apart portions of the strips 1 and 2 are bolted between splice plates 5 so that the pieces may be kept in perfect alignment, the holes for the bolts 6 being of sufficient size to permit the clamped members to expand and contract without buckling. Although the strips 1 and 2 are designed and mounted to provide for variations in length, under temperature changes, by lateral deflection, their edgewise disposition with reference to the pressure of current collectors insures a large degree of resistance to such pressure.

In order to prevent accumulations of dirt and cinders between the strips 1 and 2, the lower edges may be set slightly above the base portions of the contact pieces 3, thus leaving spaces for the escape of such material as may fall between the strips. Although the material that may descend between the strips 1 and 2 will be intercepted by the base portions of the contact pieces 3, the action of the wind and the up-and-down movement caused by the trolley will serve to dislodge the greater portion of such material.

The contact shoes 3 may be made of any desired lengths, and they may be attached to the conductor strips and to each other by any suitable means that will insure proper current conductivity and will permit them to expand and contract with changes in temperature without disturbing operating relations and conditions.

We claim as our invention:

1. A trolley conductor comprising long side-by-side strips of relatively high con-

ductivity and relatively short contact shoes of hard metal clamped between said strips and extending in proximity to the lower edges thereof.

2. A trolley conductor comprising side-by-side conducting strips of wave form and contact shoes clamped between the adjacent portions of said strips and extending adjacent to their bottom edges.

3. A trolley conductor comprising side-by-side strips of wave form, contact shoes clamped between the adjacent portions of the strips, and splice plates clamped to the ends of the contact shoes between separated portions of the strips.

4. A trolley conductor comprising side-by-side strips of wave form and contact shoes of inverted T section clamped between said strips and having scarfed ends.

5. A trolley conductor comprising side-by-side strips of wave form alternate portions of which are in juxtaposition and spaced apart, and contact shoes clamped between juxtaposed portions of the strips and extending along the bottom edges of the strips.

6. A trolley conductor comprising side-by-side strips having portions in juxtaposition and alternating portions spaced apart, contact shoes having scarfed ends and disposed end-to-end along the bottom edges of the strips, means for attaching the contact shoes to juxtaposed portions of the strips, and splice bars for the adjacent ends of said contact shoes.

7. A trolley conductor comprising long side-by-side strips having portions in juxtaposition and alternating portions spread apart, contact shoes of inverted T section clamped between the lower edges of juxtaposed portions of the strips, and splice plates clamped to the ends of the contact shoes between spread-apart portions of the strips.

8. A trolley conductor comprising side-by-side strips of relatively high conductivity and contact shoes of inverted T section clamped between said strips at intervals and having bottom surfaces of laterally convex curvature.

9. A trolley conductor comprising side-by-side strips of wave form and of relatively high conductivity, and contact shoes of relatively hard metal clamped to said strips and extending along the same in substantial alignment with each other.

10. A trolley conductor comprising side-by-side strips of wave form and of relatively high conductivity, and contact shoes of relatively hard metal extending along the said strips and having transversely convex bottom surfaces.

11. A trolley conductor comprising side-by-side strips of relatively high conductivity and contact shoes of relatively hard

metal supported by said strips and extending along the same in substantial alinement with each other.

12. A trolley conductor comprising side-by-side strips of relatively high conductivity and contact shoes of relatively hard metal clamped to said strips and extending along the same in substantial alinement with each other.

In testimony whereof, we have hereunto 10
subscribed our names this 10th day of July,
1914.

WILLIAM HOOPES.
THEODORE VARNEY.
